PRINTING TELEGRAPH APPARATUS

Charles W. Burcky, Chicago, Ill., assignor to Teletype Corporation, Chicago, Ill., a corporation of Delaware

Application March 26, 1938, Serial No. 198,178

15 Claims.

(Cl. 178—4)

This invention relates to printing telegraph systems and apparatus and more particularly to printing telegraph systems and apparatus arranged for tabulation.

5 In the operation of telegraph printers equipped with tabulating mechanisms effective to space the platen carriage or the type carriage through a plurality of spaces automatically, the time incident the movement of the carriage between 10 the respective tabulator positions is a factor which must be considered for satisfactory and reliable operation. Operation from an automatic tape transmitter requires special provisions to suspend 15 operation of the transmitter during the tabulating period and to start the transmitter promptly upon the arrival of a carriage to the desired tabular position.

The main object of the invention is the provision of control instrumentalities for use with 20 tabular recording whereby the period transmission is suspended is minimized with a consequent reduction in the loss of line time occasioned by such operation.

A further object of the invention resides in the 25 provision of a system arranged for tabular operation whereby transmission from the automatic transmitter is resumed by a condition established at a station of the system remote from the station at which the transmitter is located.

30 A feature of the invention resides in the control of interruption of transmission from the transmitter which has been stopped due to the presence of a tabulating signal in the control record and of resumption of transmission by a printing telegraph receiver located at a station remote to that of the transmitter. Such an arrangement possesses the outstanding advantages that line time is materially conserved and that a remote printer is utilized as the control 35 instrumentality for the resumption of transmission following tabulation.

The above and other objects of the invention are accomplished by the provision in a printing telegraph apparatus of the form disclosed in U. S. 45 Patent No. 1,904,164 of tabulating mechanism which includes a tabulator bar extending across the front of the machine and which is carried by brackets mounted in the typing unit and capable of oscillation toward or away from the type carriage. Carried on the tabulator bar are a number of adjustable stop control members which determine the position at which the type carriage 50 may be automatically spaced through a plurality of character spaces upon the reception of a code signal combination identified with the tabulating

function. As disclosed in the aforementioned patent, the spacing mechanism of the printing telegraph receiver includes a multi-toothed ratchet adapted to cooperate with a pair of pawls actuated by a printing bail to function as an escapement mechanism so that upon each revolution of its main shaft the spacing worm gear integral with the spacing ratchet is permitted, under normal operating conditions, to escape one tooth at a time, and hence to rotate through a 10 corresponding angle.

As also disclosed in the cited patent, a series of function levers is provided. These levers cooperate with a series of selector vanes which are set permutably in accordance with the character 15 of the received code combination signal. Included in the group of function levers is a particular lever which has been identified as a tabulating function lever. When the tabulating function lever is selected, mechanism is operated 20 whereby the upper spacing pawl is moved out of engagement with the tooth of the spacing ratchet, at which time its front end is lowered, thereby unlatching the tabulating bar to permit it to be biased by its spring toward the type carriage. 25 With the upper space pawl thus disengaged, the lower space pawl returns to its normal position free of the teeth on the spacing escapement ratchet, which permits the spacing worm to make one complete revolution instead of only one-third 30 of a revolution during the time that the main shaft rotates through one revolution. Consequently, the carriage will be spaced continuously 35 a distance for each revolution of the main shaft, which is three times that of the normal spacing distance.

The movement of the type carriage is arrested at the desired tabulating position by permitting the upper space pawl to engage with a tooth on the spacing ratchet. The latter function is effected by the coaction of a cam mounted on the type carriage and one of the adjustable stop control members secured to the tabulator bar. The tabulator bar is thus cammed forward or away from the carriage against the action of its spring, 40 and in so doing, permits the aforementioned mechanism to be restored to its normal position in latched engagement with the tabulator bar. Under such conditions the upper spacing pawl is again allowed to fall into engagement with a 45 tooth on the spacing ratchet, which thereupon arrests the type carriage.

During the time in which the carriage is moving automatically from stop to stop for tabulation, it is necessary to suspend transmission of sig- 50 55

nals from the automatic transmitter. Accordingly, the present invention provides instrumentalities for the suspension of transmission upon the presence in the control record of a tabulator signal or a particular arrangement of the perforations in the control record or strip. When such perforations are sensed, certain instrumentalities respond to control the energization of a relay whereby operation of the transmitter or distributor is suspended temporarily following the transmission to the connected line circuit of the code combination signal identified with the tabulating function which effects operation in the printing telegraph receiver connected to the line whereby its carriage will be advanced automatically to the desired tabular position. Following the transmission of the code combination signal identified with the tabulator function and with the transmitting distributor in its normal position, a relay is held energized by current flowing in the line circuit. Each of the receiving printers connected to the line circuit is equipped with a pair of contacts which are included in the line circuit; that is, the line circuit extends through such contacts. When a carriage of one of the printers arrives at the desired tabular position as determined by the position of the stop members on the tabulator bar, mechanism is operated whereby the noted contacts are opened. Opening of such contacts opens the line circuit and causes the deenergization of the relay at the transmitting station, whereupon circuit conditions are established to restart the transmitter and effect resumption of transmission to the receiving printers connected to the line circuit. Transmission continues until a tabulator signal is sensed, whereupon the operations previously described will be repeated.

A better understanding of the invention may be had from the following description when taken in conjunction with the accompanying drawings, wherein

Fig. 1 is a front elevational view of the principal part of the printing telegraph receiver showing the application of the tabulating mechanism thereto supplemented with a schematic circuit diagram illustrating the control instrumentalities of the transmitter which may be located at a station remote to that at which the receiver is located;

Fig. 2 is a transverse sectional view of the receiving printer taken approximately on line 2-2 of Fig. 1;

Fig. 3 is a cross-sectional detail view taken approximately on line 3-3 of Fig. 1;

Fig. 4 is a sectional detail view taken on line 4-4 of Fig. 1; and

Fig. 5 shows diagrammatically a detail of the tape transmitter embodied in the transmitting apparatus located at a transmitting station.

The present invention has been applied to a receiving printer of the construction shown in U. S. Patent No. 1,904,164 issued April 18, 1933, to S. Morton et al. and consequently for the details of such a printer reference should be made to such patent.

The printing telegraph receiver to which the present invention has been applied includes a primary selecting mechanism of which only the single selector magnet 8 has been shown. However, such selecting mechanism is of the sword-and-T-type disclosed in U. S. Patent No. 1,745,633 to S. Morton et al. which, incidentally, is fully and completely disclosed in Patent No. 1,904,164 cited previously. Cooperating with the primary

selecting mechanism is a secondary selector vane assembly which is indicated generally by the numeral 9. The selector vane assembly 9 controls, through a set of bell crank levers 10, a set of curved code bars 11 carried in a movable type carriage indicated generally at 12. As set forth in Patent No. 1,904,164, the type carriage is movable longitudinally with respect to a stationary platen (not shown), but manifestly the invention is not limited to its application to the particular form of receiving printer disclosed in such patent.

Disclosed in Fig. 2 is a main operating shaft 15 to which power is communicated from a continuously operating motor (not shown). Shaft 15 carries a spacing mechanism indicated generally by the reference numeral 16, as well as the selector cam assembly (not shown) which cooperates with selector magnet 8, as fully disclosed in Patent No. 1,745,633. Spacing mechanism 16 controls, through a gear 17, a shaft 18, a gear 19, and a rack 20, the movement or advancement of the type carriage 12 to form character spaces. Such movement tends to wind up a carriage return spring mechanism (not shown) which is effective upon the receipt of a carriage return signal to return the carriage 12 to its normal beginning of line position.

An auxiliary shaft 21 is mounted parallel to but above shaft 15. A number of mechanisms are mounted on shaft 21 such as, for example, printing bail 22, function lever bail 23, and the escapement elements of the spacing mechanism 16. Printing bail 22, which is actuated by a spring 24 at the proper time in the operative cycle, functions to reciprocate a pull bar operating member 25 to cause, through a pull bar 26 following its selection, the operation of a particular type bar 27.

The selector vane assembly includes a plurality of vanes 32. These vanes control a series of function levers among which and provided especially for accomplishing the objects of the present invention is a tabulating function lever 33 which, like the other function levers, is pivoted on a common pivot rod 34 and is assembled in a slot in the function lever comb 35. Function lever 33 has an individual spring 36 tensioned between the lever and the printer frame to rotate the function lever 33 clockwise about pivot 34. However, the biasing of lever 33 is restrained by the function lever bail 23 acting through rod 37 on arm 44. Lever 33 has on its arm 38 code notches and projections which cooperate with the vanes 32 of selector vane assembly 9 and which are coded to correspond to the tabulator signal; that is, upon the setting of the vanes 32 in response to the signal identified with the tabulating function, function lever 33 will be operated for performing its allocated function.

Mounted on main shaft 15 is a sleeve member 40 which comprises integral therewith a ratchet 39 and a spacing worm 31, which meshes with gear 17. Sleeve member 40 is operably connected to shaft 15 through a friction clutch (not shown) and through which it is rotated by power from shaft 15, unless blocked by the pawls of the spacing mechanism 16.

From the disclosure of Fig. 2 it is seen that ratchet 39 has three teeth 41, 42, and 43, the escapement of which will allow the type carriage 12 to be moved forward one step or character space for each actuation of printing bail 22. As indicated, the escapement mechanism comprises a pair of pawls 45 and 46 pivotally

5 mounted on shaft 21 and a lever 47 carried by printing bail 22. Spring 48 normally tends to bias levers 45 and 46 toward each other, since it has its ends connected to such levers. Lever 45 is normally urged by spring 48 in a counterclockwise direction so that its laterally disposed end 51 engages a tooth 41 of ratchet 39. Lever 46 is normally held out of engagement with ratchet 39 opposing the tension of spring 48 by lever 47 whose free end extends into the path of laterally disposed end 56.

10 Lever 47 is pivotally connected at 52 to printing bail 22 and is provided at 53 with a slot and screw adjustment whereby the correct relative 15 position of escapement levers 45 and 46 with respect to ratchet 39 may be determined.

15 As is clearly disclosed in Patent No. 1,904,164, the spacing operation occurs immediately following or subsequent to the printing of a character 20 in a manner outlined briefly below.

25 To print a character, printing bail 22 oscillates and, in so doing, controls the operation of lever 47. During the initial portion of the clockwise movement of lever 47, lever 46, under the tension of spring 48, also rotates clockwise to bring the laterally disposed end 51 into the path of tooth 42. Due to the space indicated 30 at 54 between lever 47 and the disposed end 55 of lever 45, the latter will not be acted upon and end 51 remains in engagement with tooth 41. However, on the further clockwise movement of lever 47, the end 55 of arm 45 is encountered and similar movement is thus imparted to lever 45, effecting the disengagement of end 51 from 35 tooth 41 and permitting ratchet 39 to rotate slightly in a clockwise direction under the influence of the friction clutch which is located intermediate sleeve 40 and shaft 15. The motion thus noted is limited by the engagement of tooth 40 42 with laterally disposed end 51 of lever 46, which lever, as was noted, was free to rotate in a clockwise direction under the tension of spring 48 into the path of oncoming tooth 42. Ratchet 39 is thus restrained from rotation by lever 46, 45 while the character is being printed, following 50 which printing bail 22 and associated lever 47 rotate in a counterclockwise direction actuated by a printing cam (not shown) carried on shaft 15. Restraint upon lever 45 by lever 47 through end 55 is thereby removed, permitting lever 45 to rotate in a counterclockwise direction under the influence of spring 48 into the path of oncoming tooth 43 of ratchet 39. During this counterclockwise movement of lever 47 and after the 55 aforementioned removal of restraint upon lever 45, lever 46 rotates in a like direction due to the movement of arm 47 on laterally disposed end 56, thereby disengaging the end 51 of lever 46 from tooth 42 and allowing ratchet 39 to continue its rotation until arrested by the engagement of end 51 of lever 45 with tooth 43. As a 60 result of the operation of the escapement mechanism, there is a period of overlap during which ends 51 and 57, due to the space indicated at 65 54, are effective simultaneously to prevent the escapement of ratchet 39, the ends 51 and 57 being otherwise alternately engageable to permit the escapement of ratchet 39. Since worm 31 and ratchet 39 are integrally connected to 70 sleeve 40, it is apparent that worm 31 will have normally the same intermittent or step-by-step motion as was previously described as being imparted to ratchet 39. Worm 31 is meshed with gear 17 mounted on shaft 18 and may be operatively connected thereto through a jaw clutch

75 indicated generally by the numeral 72. Worm 31 and gear 17 are so related, according to the present embodiment, that one-third revolution of worm 31 will rotate gear 17 through a distance whereby, through gear 19 and rack 20, the type carriage 12 will be advanced a distance of one character space.

80 As is apparent from the previous description, character spacing occurs automatically with the printing of each character. That is, the spacing function is incorporated into the printing operation. It is well known that there is a code combination of signal impulses allotted to each type bar, but it is possible, however, to employ a code combination of impulses commonly known as the space signal which is identified with no type bar but which will, nevertheless, initiate the operation of the printing mechanism. Under such circumstances, spacing between words is accomplished. When a space 20 signal is received in exactly the same manner as described for the operation of a pull bar 26, the printing mechanism functions in identically the same manner, except that a pull bar 26 is not operated and thus no character is recorded. 25 The spacing mechanism will, however, be operated to effect spacing of the type carriage one character space.

30 With regard particularly to the specific embodiment of the present invention, continuous spacing of the type carriage may be effected upon the receipt of a code combination of signal impulses identified with the tabulating operation. The function of such a signal combination is to initiate the operation of the tabulating mechanism.

35 The mechanically operated tabulating mechanism comprises a tabulating bar 65 which extends across the front of the printing telegraph receiver, as shown in Fig. 1, and which has two 40 depending arms 66 and 67 which are pivotally mounted on a bracket 68. Thus, tabulator bar 65 is adapted to be oscillated toward and away from the type carriage 12. Bar 65 has a longitudinal slot 69 extending substantially throughout its entire length. In slot 69 are carried adjustably movable stop members 70 which are clamped to the bar 65 by means of screws 71 cooperating with a suitable clamp. As indicated in Fig. 4, the stop members 70 are provided with an inclined or cam portion 73 conformed to produce a quick action upon cooperating with a cam element 74 carried by type carriage 12, in order to terminate suddenly the tabulating operation.

45 Tabulator bar 65 is also provided intermediate the depending portions 66 and 67 and suitably positioned relative to function lever 83 with another depending portion 75. Attached to and depending from portion 75 is a member 83, the 50 lower end of which is provided with an aperture 76 having its upper lefthand corner (as viewed in Fig. 2) conformed so as to provide a reentrant stepped portion 77. The tabulator bar 65 is normally urged in a counterclockwise 55 direction, as viewed in Fig. 2, by a spring 78 (Fig. 1).

60 Cooperating with the stepped portion 77 is one arm 79 of a lever 80 pivotally carried at 65 81 on a bracket 82 screwed to the function lever 70 comb 35. The extremity of arm 79 has a laterally disposed portion 81 which cooperates with portion 77 of member 83. At the end of arm 84 of lever 80 is carried a vertically extending member 90, the upper end of which is provided 75

with an open ended slot adapted to engage a pin 91 secured to escapement lever 45.

Function lever 33 has a horizontal portion 86 so conformed that its extremity 88 engages the lower edge of arm 84 of lever 80 so that when function lever 33 is permitted to rotate in a clockwise direction under the action of its spring 36 due to the proper setting of vanes 32 in response to a signal code combination identified 10 with the tabulating function, the end 88 thereof is raised, causing lever 80 to rock in a clockwise direction against the tension of its spring 92. The end 87 of arm 79 is thereby moved downwardly clear of portion 77, thus permitting spring 15 88 to urge tabulator bar 65 inwardly (or toward the left as viewed in Fig. 2) until wall 89 of member 83 engages portion 87. Adjustable stops 70 are therefore moved inwardly into the path of cam member 74 which is pivoted at 93 on a portion 94 integrally formed on a bar 95 which is comparable to bar 53 shown in Fig. 1 of Patent No. 1,904,164 and which is employed for retaining the bell crank levers 10 in operative relation to vanes 32. Cam 74, like bar 95 and bell 20 cranks 10, is moved with the type carriage 12 for carriage spacing and normally tends to rotate in a clockwise direction about its pivot 93, due to the action of its spring 96, but its clockwise rotation is limited by the coaction of stop 25 pin 97 carried thereon with the end of bar 95. Consequently, upon the rightward movement of type carriage 12 (as viewed in Figs. 1 and 4) cam 74, due to its limited rotatability in a clockwise direction will, by its camming action on stop 30 member 76, rock tabulator bar 65 outwardly, but upon the leftward movement of type carriage 12, cam 74, upon striking the series of stop members 70, will be rotated counterclockwise against the action of spring 96 sufficiently to be ineffective with cam portions 73.

Upon the clockwise rotation of lever 80, due to the selection of function lever 33, arm 84 and consequently member 90 carried thereby will be raised, and in so doing will, through pin 21, lift escapement lever 45 free of the teeth of the ratchet 39 which, since the lever 45 is (after its oscillation by bail 22) prevented from engaging the teeth of ratchet 39 due to being held in its retracted position by lever 47, permits worm 50 gear 31 to make one complete revolution instead of one-third of a revolution during the time that the main shaft 15 rotates through one revolution. Carriage 12 will be spaced continuously a distance per revolution of shaft 15 which is three 55 times that of normal spacing, as long as the escapement lever 45 is held out of operative engagement with ratchet 39, which is maintained in this position due to the engagement of portion 57 with the underside of stepped portion 77. Carriage 12 will move continuously until cam 74 contacts with one of a series of stops 70, when, through stop 70, cam 74 will urge tabulator bar 65 outwardly or in a clockwise direction, as viewed in Fig. 2, to disengage portion 87 from portion 65 77, whereupon lever 80 will again be rotated in a counterclockwise direction by its spring 92 into the position shown in Fig. 2. The member 90 carried on arm 84 of lever 80 will again be lowered, permitting escapement lever 45 under the 70 action of spring 48 to engage one of the teeth 41, 42, or 43 of ratchet 39.

Function lever 33 will be returned to its unselected position at the completion of the first revolution or cycle of operation of main shaft 75 15 because of the fact that during the cycle,

pursuant to the reception of the tabulating signal, the function lever bail 23 will have been reciprocated once so that rod 31, upon the down stroke of bail 23, will permit spring 36 to urge lever 33 into cooperative relation with vanes 32 only long enough to effect the selection and hence the resulting disengagement of pawl 45, whereafter rod 31, upon its upward or return movement, will cam the function lever 33 through arm 44 away from the vanes 32 where it will be held until the 10 reception of another code signal.

During the time that the carriage 12 is moving to effect tabulation; that is, from the time the tabulation signal is received up to the time when cam 74 engages the next stop 70, the transmission and reception of succeeding character code signals must be prevented, inasmuch as signals sent or received during the continuous movement of the type carriage for tabulation may not properly effectuate printing. Such a condition is especially true when automatic transmission, that is, transmission from a perforated tape, is utilized. Consequently, the present invention has as one of its objects the provision of means for suspending the transmission of code signals 20 during the tabulating operation.

Tabulator bar 65 has a depending tongue 98, the lower end of which cooperates with a bell crank lever 99 pivoted at 100 (Figs. 1 and 3) to a base 101. One arm of bell crank 99 has one surface inclined to cooperate with the beveled end of tongue 98, and the other arm of bell crank 99 engages a pin 102 secured to lever 103 which is also pivoted at 100. Extending between arms on bell crank 99 and lever 103 is a spring 104. Lever 103 is urged normally by a spring 107 against a stop pin 108 to allow contacts 109 to close. Contacts 109 are connected in a series circuit with a line conductor 106 and the windings 40 of the electromagnet 8 of the primary selecting mechanism.

Also as disclosed in Fig. 1, the line conductor 106 extends to other printing telegraph stations such as 107 and 108 where a printing telegraph receiver similar to that described above is located. It is, of course, understood that additional stations may also be connected with line conductor 106.

One terminal of the single selector magnet 8 of the primary selecting mechanism is connected 50 to a line conductor 109 extending to a distant station indicated by the numeral 110 where transmitting apparatus of the construction as generally shown in U. S. Patent No. 1,632,297 to E. E. Kleinschmidt may be located. Significant, 55 however, is the fact that according to the present invention, the tape transmitter or tape sensing mechanism is arranged with an extra set of contacts, the function of which will appear hereinafter.

The transmitter shown diagrammatically in Fig. 1 as being located at station 110 includes a set of tape sensing elements 111 (Fig. 5) which, under the control of a tape or signal storing medium 112, controls a corresponding set of contacts 113 connected directly on one side to a source of current and on the other through individual conductors 114 to segments 115 of a distributor 116. A second set of contacts 117 are also controlled by the tape sensing elements 111 and are actuated in response to the perforations in tape 112 in the same manner as are contacts 113. However, unlike contacts 113 which impress current from the common source of battery upon any one of the contacts thereof that are 75

- closed, certain ones of the contacts 117 are permanently connected in series to correspond to the predetermined code combination allotted to the figures shift signal and to the predetermined 5 code combination allotted to the tabulation signal. For example, with the contactors 118, Fig. 5, in the dotted line position shown in Fig. 1, which is identified with the figures shift signal, a circuit will be completed extending from battery, 10 through the contactors 118 and the respective contacts 117 in series, conductor 119 and the winding of slow-to-release relay 120 to ground. However, with all of the contactors 118 in the dotted line position except the lowermost contactor, as viewed in Fig. 1, and with such contactor 118 moved to its left-hand position as viewed in such figure, a circuit will be completed 15 extending through the left-hand front contact of relay 120.
- 20 The distributor 116, in addition to the segments 115, includes a brush arm 121 secured to a shaft 122 to which power is communicated from a continuously operating motor (not shown) through a friction clutch (not shown), a continuous ring 123, and stop and start segments 124 and 125, respectively. Brush arm 121, which carries a brush adapted to bridge the segments of the outer ring with the continuous ring 123 which is connected to line conductor 109, is normally held against rotation by the armature 126 of stop magnet 127 which has its winding connected with battery 128 through a manual switch 129 and the extreme left-hand armature and back contact of relay 130. With switch 129 closed and with relay 130 deenergized, electromagnet 127 will be energized and armature 126 will be held out of the path of brush arm 121.
- Also secured to shaft 122 are two cams 131 and 132. Cam 131 cooperates with pivoted arms 40 133 and 134 to control certain electrical circuits, as will be later described, while cam 132 operates a pivoted arm 135 against the tension of a spring 136 to hold mechanically armature 137 of an electromagnet 138 against its pole pieces. As shown in Fig. 1, arm 135 is held out of engagement with armature 137 when shaft 122 is in its normal or arrested position. Immediately that shaft 122 moves from its rest position, arm 135, by the action of its spring 136, engages armature 137 and moves it mechanically against the pole pieces 45 of relay 138.
- In addition to relay 138, a relay 140 is provided which controls, through its upper armatures and back contacts, an energizing circuit for the upper winding of relay 138 and through its lower armatures and front contacts the energizing circuit for the lower windings of relay 138. The armatures of relay 140 are adjusted such that contacts are made before the others are broken; that is, the contacts shown in Fig. 1 as 50 normally closed are maintained closed upon the energization of relay 140 until the front contacts thereof are closed.
- When a figures shift signal appears in tape 60 112, sensing elements 111 operate to set contacts 113 and contactors 118. Through contacts 113 and the operation of distributor 116 a code combination of impulses identified with the figures shift signal will be transmitted over line conductors 109 and 106 to the printing telegraph receiver shown in Fig. 1 and the printing telegraph receiver located at stations 107 and 108, respectively. Such printing telegraph receivers respond to their selecting mechanisms in accordance with the transmitted code combination 65
- of signaling impulses. Through contactors 118 a circuit is completed for relay 120 extending from grounded battery, through contacts 117 and contactors 118 which will be in the dotted line position shown in Fig. 1, conductor 119, and the winding of relay 120 to ground. Relay 120 is energized and closes, through its left-hand front contact, a circuit extending to the winding of relay 130 and through its right-hand front contact a locking circuit for itself extending to battery connected to pivoted arm 133. However, except when shaft 122 is in its normal or rest position, the circuit controlled by arm 133 will be open. Current continues to flow through the winding of relay 120 from battery connected to 10 contactors 118, for the contactors 118 remain in engagement with the contacts 117 for the greater part of the cycle of distributor 116 or until the tape sensing elements 111 are withdrawn from the tape which occurs near the end of the cycle 15 of distributor 116. Relay 120, however, is slow to release and retains its armatures in their attracted position until arm 133 engages its contact due to the action of cam 131, when a locking circuit for relay 120 will be completed extending 20 from grounded battery, through arm 133, right-hand armature and front contact and winding of relay 120 to ground. Relay 120 will thus be maintained energized. 25
- Following the transmission of the signal impulses for the figures shift signal, the tape 112 will be advanced through mechanism provided therefor to present the next transverse row of code perforations in alignment with the sensing elements 111. If the next transverse row of perforations corresponds to the tabulation signal, the contacts 118 will be correspondingly set and a circuit will be completed whereby relay 130 will be energized. This circuit may be traced from grounded battery, through the contacts 117 and 30 contactors 118, left-hand front contact and armature of relay 120 and the winding of relay 130 to ground. Relay 130, in energizing, opens at its left-hand armature the energizing circuit for electromagnet 127 which is thereupon deenergized and armature 126 is moved into the path of brush arm 121 so that upon the completion of the cycle of rotation of brush arm 121, it will engage the latch on armature 126 and will be held against rotation pending the energization 35 of electromagnet 127. A locking circuit for relay 130 extends from grounded battery, through element 141 under the control of relay 138, middle armature and front contact and winding of relay 130 to ground. Relay 130 is thus held energized. 40 Through the extreme right-hand armature and front contact of relay 130 a circuit extends to relay 140 which will be energized, when cam 131 is in its normal or arrested position and pivoted member 134 is in engagement with the electrical 45 contact associated therewith. The back contacts of relay 140 are maintained closed pending the closure of the front contacts thereof so that for an instant current flows through both sets of windings of relay 138. With the upper back 50 contacts of relay 140 opened, relay 138 is maintained energized since current now flows from grounded battery, through segment 124, the brush carried by brush arm 121, ring 123, armature 142 of relay 140, lower windings of relay 138, 55 armature 143 of relay 140, line conductor 109, winding of the single selector magnet 3, contacts 149, line conductor 106, and through the printing telegraph receivers located at stations 107 and 108 which have their printing telegraph 60 receivers located at stations 107 and 108 which have their printing telegraph 65 receivers located at stations 107 and 108 which have their printing telegraph 70 receivers located at stations 107 and 108 which have their printing telegraph 75 receivers located at stations 107 and 108 which have their printing telegraph 75

receivers equipped with contacts 144 and 145 corresponding to contacts 149. Relay 138 is thus maintained energized and the locking circuit for relay 130 is maintained closed through arm 141.

5 When the sensing elements 111 sensed the transverse row of perforations in tape 112 for the tabulation function appearing after the figures shift signal, contacts 113 were set accordingly and during the cycle of rotation of brush 10 arm 121 impulses identified with the tabulation operation were transmitted over conductors 109 and 106 and were impressed upon the single selector magnet at each of the connected stations.

In response to the operation of the single selector magnet, the selecting mechanism for the printing telegraph receivers at the respective stations operates, and causes the setting of the vanes 32, whereupon the function bar 33 identified with the tabulator operation is operated to cause the 15 pawl 45 to be moved free of the teeth on ratchet 39 so that the carriage 12 advances continuously until cam 74 engages a stop element 70 mounted on tabulator bar 65. When cam 74 engages a stop 70, tabulator bar 65 is moved in a clockwise direction, as viewed in Fig. 2, the pawl 45 is restored to the position shown in Fig. 2 or a 20 position where member 51 lies in the path of tooth 41, 42, or 43. Arm 98 is moved to the solid line position shown in Fig. 3 and in moving to 25 such position rotates bell crank lever 99 against the action of spring 104 when function bar 33 operates. Lever 103 remains in the position shown against stop pin 148 due to the action of spring 147. When tabulator bar 65 is moved 30 by cam 74, arm 98 is restored to the dotted line position shown in Fig. 3 and in so moving, rotates bell crank 99 in a direction such that its lower arm engages pin 102 and rotates lever 103 against the action of spring 147, whereupon 35 contacts 149 are opened only momentarily to transmit a start signal and thus unshift all printers on the line circuit without printing a false character. Engagement of arm 98 with the upper arm of bell crank 99 is adjusted to provide 40 for proper time and duration of opening of contacts 149 to produce the desired condition.

Upon the opening of contacts 149, 144, or 145, depending upon which contact is first operated, or depending upon the printer whose contact is 45 adjusted to exercise control to open the line circuit and control the restarting of transmission, current is removed from the lower windings of relay 138, and since the circuit for the upper windings thereof is opened at the uppermost back contacts of relay 140, now energized, relay 138 is deenergized so that its spring 146, which has a lower tension than spring 136, moves arm 141 free of its electrical contact, whereupon the holding circuit of relay 130 is opened. Relay 130 is thus deenergized to cause the energization of electromagnet 127, which removes armature 126 from the path of arm 121 to allow such arm to rotate. Cam 131 is rotated, opening contacts 133 and 135. Opening of contact 133 opens the holding circuit 50 of relay 120, whereas contact 134 in opening removes the ground connection from relay 140 which was deenergized upon the deenergization of relay 130. Relay 140 completes, through its upper back contacts, an energizing circuit for 55 relay 138. The characteristics of relay 138 may not be such to cause the attraction of the armature 137 of relay 138 upon the closure of the back contacts of relay 140 and consequently cam 132 is arranged shortly after its release with shaft 122 to move arm 135 downwardly and force ar-

mature 137 mechanically against its pole pieces independently of the circuit controlled by relay 140. However, with current flowing through the upper windings of relay 138, armature 137 will be held attracted.

Particularly significant with regard to the circuit arrangement previously described is the fact that the windings of relay 138 are not included in the line circuit during the transmission of code combinations of signaling impulses 10 but are connected therein only upon the energization of relay 140, the energization of which occurs only when a tabulator signal follows immediately a figures shift signal in the tape. Should a tight tape condition develop immediately following the energization of relay 120, advancement of the tape will cease, but relay 120 remains energized. Upon resumption of tape advancement, the tabulator signal will be sensed and relay 130 will be energized to effect the desired control. Consequently, no additional impedance is included in the line circuit to alter or change the characteristics of the line. Also, by using a relay 138 having the same electrical characteristics as selector magnet 8, the operating conditions of the line circuit can be easily determined, for the use of a relay 138 is the same as if another receiving printer were added to the circuit.

While the invention has been disclosed and described with regard to a particular type of receiving printer, it is obvious that other forms and types of receiving printers might be utilized for the achievement of the present invention without departing from its scope and spirit.

What is claimed is:

1. In a telegraph system, a line circuit extending between a plurality of stations, a transmitter at one of said stations, a printing telegraph receiver at the other station responsive to impulses transmitted from said transmitter, said transmitter including a distributor and a record reader for sensing the control indicia on a control strip, means for discontinuing transmission from said transmitter, means responsive to two successive predetermined groups of control indicia on said strip for operating said means to discontinue transmission from said transmitter, and means operated by said receiver for establishing a condition to resume transmission from said transmitter.

2. In a telegraph system, a line circuit extending between a plurality of stations, a transmitter at one of said stations, a printing telegraph receiver at the other station responsive to impulses transmitted from said transmitter, said transmitter including a distributor and a record reader for sensing the control indicia on a control strip, means for discontinuing transmission from said transmitter, means responsive to predetermined control indicia on said strip for operating said means to discontinue transmission, and means remote from said transmitter and local to the receiver at any of said stations for starting transmission upon the establishment of a predetermined condition in said line circuit.

3. In a telegraph system, a single line conductor extending between a plurality of stations, a transmitter at one of said stations, a printing telegraph receiver at each of the other stations responsive to impulses transmitted from said transmitter, said transmitter including a distributor and a record reader for sensing the control indicia on a control strip, means for discontinuing transmission from said transmitter,

- means responsive to a predetermined condition in the record reader for operating said means to discontinue transmission, and means included in a receiver at a station in said line circuit remote from said transmitter for establishing a condition whereupon said transmitter resumes the transmission of impulses.
4. In a telegraph system, a line circuit extending between a plurality of stations, a transmitter at one of said stations, a printing telegraph receiver at each of the other stations responsive to impulses transmitted from said transmitter, said transmitter including a distributor and a record reader for sensing the control indicia on a control strip, means for discontinuing transmission from said transmitter, means responsive to a predetermined group of control indicia on said strip for operating said means to discontinue transmission, means in each of said receivers responsive to the establishment of a predetermined condition, and means in said transmitter responsive to the operation of said last mentioned means in any of said receivers for restarting said transmitter.
5. In a telegraph system, a line circuit extending between a plurality of stations, a transmitter at one of said stations, a printing telegraph received at each of the other stations responsive to impulses transmitted by said transmitter, said transmitter including a distributor and a record reader for sensing the control indicia on a control strip, means for controlling transmission from said transmitter, a pair of relays operated successively in response to two successive predetermined groups of control indicia on said strip for operating said means to discontinue transmission, and means controlled by one of said receivers for establishing a condition to resume transmission from said transmitter.
6. In a telegraph system, a line circuit extending between a plurality of stations, a transmitter at one of said stations, a printing telegraph receiver at each of the other stations responsive to impulses transmitted from said transmitter, said transmitter including a distributor and a record reader for sensing the control indicia on a control strip, means for controlling transmission from said transmitter, a pair of relays operated successively in response to two successive predetermined groups of control indicia on said strip for operating said means to discontinue transmission, and means responsive to a predetermined condition for causing the release of one of said relays to restart transmission from said distributor.
7. In a telegraph system, a line circuit extending between a plurality of stations, a transmitter at one of said stations, a printing telegraph receiver at each of the other stations responsive to impulses transmitted from said transmitter, said transmitter including a distributor and a record reader for sensing the control indicia on a control strip, means for controlling transmission from said transmitter, a pair of relays operated successively in response to two successive predetermined groups of control indicia on said strip for operating said means to discontinue transmission, and means in the transmitter responsive to a predetermined condition in one of the receivers for causing the de-energization of one of said relays whereupon transmission from said transmitter is resumed.
8. In a telegraph system, a line circuit extending between a plurality of stations, a transmitter at one of said stations, a printing telegraph receiver at each of the other stations responsive to impulses transmitted from said transmitter, said transmitter including a distributor and a record reader for sensing the control indicia on a control strip, means for discontinuing transmission from said transmitter upon the establishment therein of a predetermined condition established by said control strip, means controlled by said tabulating mechanism of the receiver at any of said stations for establishing a condition in said line circuit, and means responsive to the establishment of said condition in said line circuit for resuming transmission from said transmitter.
9. In a telegraph system, a line circuit extending between a plurality of stations, a transmitter at one of said stations, a printing telegraph receiver at each of the other stations responsive to impulses transmitted from said transmitter and including a tabulating mechanism, said transmitter including a start-stop distributor and a record reader for sensing perforations on a perforated tape, means for arresting the operation of said distributor to discontinue transmission of impulses over said line circuit, means operated by the tabulating mechanism of a receiver in response to the transmission of a group of impulses from said transmitter for opening the line circuit, and means included in said transmitter responsive to the opening of said line circuit at any of said stations for restarting said distributor for the resumption of transmission of impulses determined by the perforations in said tape.
10. In a telegraph system, a line circuit extending between a plurality of stations, a transmitter at one of said stations, a printing telegraph receiver at each of the other stations responsive to impulses transmitted from said transmitter and including a movable carriage and a tabulating mechanism responsive to a predetermined group of impulses transmitted from said transmitter for causing the continuous advancement of said carriage, said transmitter including a distributor and a record reader for sensing the control indicia on a control strip, means for discontinuing transmission from said transmitter following the transmission of a group of impulses identified with the operation of the tabulating mechanism in the receiver whereby said carriage moves continuously, means operated when said carriage reaches a predetermined point, and means in the transmitter responsive to the operation of said last mentioned means of the receiver at any station for starting transmission from said transmitter.
11. In a telegraph system, a line circuit extending between a plurality of stations, a transmitter at one of said stations, a printing telegraph receiver at each of the other stations responsive to impulses transmitted from said transmitter, said transmitter including a distributor and a record reader embodying means for sensing the control indicia on a control strip, two sets of elements controlled by said indicia sensing means, means for discontinuing transmission from said transmitter, and means controlled by a predetermined successive setting of one of the means controlled by said indicia sensing means for operating said transmission discontinuing means to discontinue transmission.
12. In a telegraph system, a line circuit extending between a plurality of stations, a transmitter at one of said stations, a receiver at the

- other station responsive to impulses transmitted by said transmitter, said transmitter including a distributor and a record reader for sensing the control indicia on a control strip, a slow-to-release relay responsive to a predetermined group of control indicia on said strip, and means controlled by said relay and operated, provided the next succeeding group of control indicia is of a predetermined character, for discontinuing transmission from said transmitter. 5
13. In a telegraph system, a line circuit extending between a plurality of stations, a transmitter at one of said stations, a receiver at the other station responsive to impulses transmitted by said transmitter, said transmitter including a distributor and a record reader for sensing the control indicia on a control strip, a slow-to-release relay responsive to a predetermined group of control indicia on said strip, means controlled by said relay and operated, provided the next succeeding group of control indicia is of a predetermined character, for discontinuing transmission from said transmitter, means in the receiver responsive to a particular group of impulses from said transmitter, and means responsive to said last mentioned means for causing said transmitter to resume transmission of impulses in accordance with the control indicia on said strip. 10
14. In a telegraph system, a line circuit extending between a plurality of stations, a transmitter at one of the stations, a printing telegraph receiver at the other station responsive to impulses transmitted by said transmitter, said transmitter including a distributor and a record reader for sensing the control indicia on a control strip, means for discontinuing transmission from said transmitter upon the establishment of a predetermined condition, means normally unresponsive to signals impressed on said line circuit, and means operated through the operation of said transmission discontinuing means for rendering said last mentioned means responsive to impulses impressed on the line circuit. 15
15. In a telegraph system, a line circuit extending between a plurality of stations, a transmitter at one of the stations, a printing telegraph receiver at the other station responsive to impulses transmitted by said transmitter, said transmitter including a distributor and a record reader for sensing the control indicia on a control strip, means for discontinuing transmission from said transmitter upon the establishment of a predetermined condition, means normally unresponsive to signals impressed on said line circuit, means operated through the operation of said transmission discontinuing means for rendering said last-mentioned means responsive to impulses impressed on the line circuit, and means in said receiver for impressing on the line circuit the impulses for operating the means normally unresponsive to signals whereby a condition is established for resuming transmission from said transmitter. 20
